United States Patent Office

Des. 201,818
Patented Aug. 3, 1965

201,818

MOTOR DRIVEN POWER UNIT

Dave Chapman and Robert C. Le Sueur, Chicago, Ill.,
assignors to Scovill Manufacturing Company, Water-
bury, Conn., a corporation of Connecticut

Filed Oct. 19, 1964, Ser. No. 82,229

Term of patent 14 years

(Cl. D44—1)

Fig. 1

Fig. 2

FIG. 3

FIG. 5

FIG. 4

FIG. 6

FIG. 1 is a perspective view of a motor driven power unit showing our new design;

FIG. 2 is a side elevational view;

FIG. 3 is a top plan view;

FIG. 4 is an end elevational view, the opposite end being identical thereto;

FIG. 5 is an elevational view, partly in section, in the plane of the line 5—5 of FIG. 4; and

FIG. 6 is a bottom view thereof.

We claim:

The ornamental design for a motor driven power unit, as shown and described.
